UNITED STATES PATENT OFFICE.

JOSEPH GOULDBOURN AND FRED RICKS, OF LEICESTER, ENGLAND, ASSIGNEES TO
UNITED SHOE MACHINERY CORPORATION, OF PATERSON, NEW JERSEY, A COR-
PORATION OF NEW JERSEY.

SEWING MACHINE.

Application filed February 3, 1921. Serial No. 442,040.

To all whom it may concern:

Be it known that we, JOSEPH GOULDBOURN and FRED RICKS, subjects of the King of Great Britain, residing at Leicester, in the 5 county of Leicester, England, have invented certain new and useful Improvements in Sewing Machines; and we do hereby declare the following to be a full, clear, and exact description of the invention, such as will 10 enable others skilled in the art to which it appertains to make and use the same.

This invention relates to chain stitch or other straight hooked needle boot or shoe sole sewing machines with a rotary horn 15 peculiar in that the horn rises and falls in accordance with variations in thickness of the work and thereby controls movement of the needle. A machine so organized is illustrated and described in the patent to Bates 20 No. 1,080,879, dated December 9, 1913, and it is the principal object of the present invention to improve this machine. The machine of the aforesaid specification was intended to operate at unusually high speed 25 and the principal objects of the present invention are to provide various improvements increasing the reliability of operation of such a machine at high speed, its endurance and improving the character of the work produced by it.

There will be described hereinafter in detail and by way of example, a machine which embodies in a convenient form the various features of the invention which features will 35 respectively become evident to those skilled in the art from this description and which include improved means to control the positioning of the work during stitch formation, improved means to facilitate the handling 40 of the work as the sewing is carried round the toe of a boot or shoe and particular and novel organizations of the various groups of parts tending to rigidity, simplicity, durability and access as well as certain time 45 relationships between the movements of these parts which trials have shown us to be particularly advantageous.

According to one important feature of the invention there is provided a device operating in time relation to other operations of the machine to exercise locking action on the horn.

According to another feature of the invention the power shaft which carries the ro-

tary needle-actuating means and actuators 55 for other motions of the machine extends from front to rear of the machine (considered from the operator's standpoint) and a link and lever mechanism operated by the needle-actuating means also extends in a direction from front to rear of the machine.

Other features of the invention consist in certain constructions, arrangements and combinations of parts hereinafter described and claimed, the advantages of which will 65 be obvious to those skilled in the art from the following description.

The illustrative machine now to be described is a machine with needle actuating and control mechanism and horn mechanism 70 of the general character of that described in said Patent No. 1,080,879 with reference to Figure 1 of the drawings thereof, the main shaft speed being controlled by the rotation of the horn in the manner indicated in the 75 patent to Bates No. 1,140,349, dated May 25, 1915, and by mechanism generally similar to that described in the last mentioned patent although amongst other differences a clutch mechanism as illustrated and described in the patent to Jerram 1,124,620, dated Jan. 12, 1915, is employed. In addition the machine embodies work feed and work clamping mechanism of a character 80 similar to that illustrated and described in 85 the patent to Goddard and Jerram No. 1,353,827, dated September 28, 1920.

In the accompanying drawings,

Figure 1 is a side elevation of the machine with parts of the casing broken away to 90 show the mechanism; Fig. 2 is a front view, partly in section, of the upper part of the machine; Fig. 3 is a part sectional view of one form of horn-locking mechanism; Figs. 4, 5 and 6 are detail views showing an alternative horn-locking mechanism; Fig. 7 is a vertical sectional view, partly in elevation, of the lower portion of the base of the machine illustrating particularly the treadle mechanism; Figs. 8 and 9 are plan and side 100 elevations respectively of link mechanism connecting the horn and the needle bar.

The vertical rod 3 rising at the rear of the machine column 1 and by which the vertical movement of the horn 5 is transmitted to the needle controlling mechanism has its upper end pivoted at 7 to the rear end of a horizontal lever 9 the opposite end of

which is fulcrumed on the machine head at 11, and which intermediate its ends has fulcrumed to it the lower end of an upwardly extending link 13 the upper end 5 of which is forwardly curved and forked at 15 to receive between its forked end portions the rearward end of a further link 17 which link end as well as the fork end of the vertical link is pivoted to a transverse 10 pin 19, the end portions of which form pivots for a link pair 21 the opposite ends of which are pivoted to the corresponding forks 23 of a forked bell crank lever, pivoted to the frame at 25 and terminally 15 forked at 27 to embrace the link 29 by which it is connected to the needle bar 31 and to which it is pivoted at 33.

The bell crank lever is formed by the fusion of two of the corresponding arms 20 of two bell crank levers side by side so as to leave between the other two arms and the fulcrum members of the levers a space into which may rise the forward end of the needle-actuating rocker 35 between the 25 forked portions of the forked forward and slightly uprising end of which rocker the forward end of the link 17 aforesaid is pivoted at 37.

The rocker is pivoted intermediate its 30 ends to the machine head at 39 and rearward of its pivot is forked to allow of the passage through it of the upwardly extending link 13 and to receive between its forked ends a universal connection by which 35 it is coupled to the lower end of a connecting rod 41 the upper end of which embraces a ball-shaped crank pin 43 extending between discs 45 on the cam shaft 47 which runs from front to rear of the machine in the head 49.

On the stud 51 by which the lower end 45 of the link 13 aforesaid is fulcrumed to the horizontal lever 9 is a head engaging a horizontal slot 52 in a vertical rod 53 guided in upper and lower bearings in the head. The upper end of the vertical rod has formed on it a flat surface, which during a part of the cycle of the machine, is engaged by a cam 55 to lock the rod 50 against downward movement and through the connections aforementioned to lock the horn against upward movement. The cam projects through an opening in the upper bearing of the vertical rod, into engagement with the rod and is formed on a lever 55 57, fulcrumed (between ears 58 projecting from the upper bearing of the vertical rod) on a horizontal shaft 59 parallel with the cam shaft having fast to it at one end an arm 61 at the end of which is a stud carrying a cam roll, positioned in a cam track formed in one of the two faces of a cam 63 fixed on the cam shaft just forwardly 60 of the needle actuating crank. The horizontal shaft has on it a flat surface 65,

and the cam lever 57 has on the side of its hub remote from the cam surface a boss in which are a set screw 67 and a plunger 69 backed by a spring 70 and by a spring adjusting screw 71. The set screw, 70 plunger and flat face on the shaft are so arranged that when the shaft 59 is turned by its cam the flat face 65 will, through the plunger, turn the cam lever 57 yieldingly 75 in a direction to lock the vertical rod 53 and when the horizontal shaft is turned in the opposite direction the flat face will engage the set screw 67 in the cam lever and will positively turn the lever to disengage the cam 55 from the rod and unlock it.

In an alternative locking mechanism for the vertical rod 53 (see Figures 4, 5 and 6). the upper end of the rod is cylindrical and is guided in a bearing in the head. The rod above the bearing passes through a circular collar 72 in the center of which is a triangular opening 73 having its corners rounded and on the outer edge of which are circular recesses 75 opposite each straight face of the opening. The collar is vertically positioned at one side of the vertical rod between an upwardly projecting lip 77 formed on the bearing and a cap 79 fastened on the upper face of the bearing and its opposite side is supported by a shoulder 81 formed on a vertical plunger 83 guided in a bore in the bearing parallel to the vertical rod. The reduced portion of the plunger, where the shoulder is formed, engages one of the aforementioned circular recesses. The plunger is pressed downward by a spring 85 in the bore in the bearing, the tension of the spring being adjustable by means of a screw 87 threaded in the bore. The lower end of the plunger rests on an upwardly turned end of one arm of a cam lever 89 fulcrumed on a horizontal shaft parallel to the cam shaft. The other arm of the cam lever has projecting laterally from it a stud on which is a cam roll positioned in a cam track in a similar location to that operating the arm 61. When the cam lever is rocked in one direction by its cam track it will raise the plunger 83 and will align the sides of the triangular opening in the collar 72 with the rod 53 and will allow the rod to pass freely through the collar, and when the cam lever is rocked in the opposite direction the spring 85 presses down the plunger 83 and with it one side of the collar and binds the edges of the triangular opening in the collar against the rod and locks the rod against downward movement.

The needle bar 31 slides in vertical bearings 91, 93 at the front of the head of the machine and at its lower end is split vertically at 95 for a short distance and has a vertical central bore in which the needle

is clamped by a nut 99 and bolt 97, the latter passing through the needle bar at right angles to the slit in the bar, and being bored transversely of its length to allow 5 the needle to pass through it. The needle bar at its upper end is forged to receive the lower end of the link 29 pivoted to it at 101.

The head 103 of the bolt 97 has a vertical bore which forms a bearing for a vertically extending part of the cast-off 105, the upper end of which is clamped by a set screw in a block 107 which block has a horizontal rearwardly extending pin 109 which has a bearing in one end of an arm 111 the other end of which is pinned to a horizontal rearwardly extending shaft 113 having a bearing in the head of the machine. To the other end of this shaft is pinned a second 20 arm 115 to the forked end of which is pivotally connected at 117 an upwardly extending link 119 formed at its upper end to embrace a cam on the cam-shaft of the machine just forward of the cam 63. The 25 needle bar has formed on it at one side a vertical groove in which the vertical part of the cast-off is situated, and at the upper end of this groove the needle bar is cut away to form a clearance for the block in 30 which the upper end of the cast-off is clamped.

The work feed point 123 is fastened by a set screw in the lower end of a vertical bar 125 arranged by the side and to the right of the needle bar viewing the machine from the front and having its lower end inclined towards the path of the needle which bar has towards the lower end of its vertical part a vertical slot 127 which embraces a block 35 129 fulcrumed on a pin 131 adjustably mounted in a vertical slot 133 formed in a vertical arm 135 which is pinned to one end of a horizontal rearwardly extending shaft 137 having a bearing in the head of the machine frame and having fixed on its opposite end a second and horizontal arm 139 in the forked outer end of which is pivoted on a horizontal pin 141 the lower end of an 40 upwardly extending link 143. The upper end of the link is pivoted in the forked outer end of a cam lever 145 which is pivoted at its opposite end on a horizontal stud 147 fixed in the head of the machine. The cam lever has on a stud projecting laterally rearwardly from it between its pivoted and 45 forked ends a cam roll 149 positioned in a cam groove formed in the forward face of the cam 63. The vertical slots 127 and 133 in the feed-point bar and lever are so arranged that at the end of the feeding movement of the feed point the slots coincide one with the other and the pin 131 connecting the bar and lever may be adjusted in the 50 slots to vary the length of feed without 55 altering the position of the feed-point at the

end of the feed, the variation in length of feed taking place at the beginning of the feed.

The presser foot 151 is fastened by a clamp screw on to the lower end of a second vertical bar 153, guided in bearings 155 and 70 157 in the head of the machine parallel to the needle bar and to the right of the feed point bar viewing the machine from the front. The lower end of this bar is also inclined towards the path of the needle and is 75 vertically slotted at 159 about midway of its vertical length to receive a compression spring 161 which bears at its lower end against the lower end of the slot and at its upper end against a pin 163 projecting from the head of the machine into the slot. The upper end wall of the slot rests on the opposite (the upper) side of the pin when no work is in the machine and limits the downward movement of the presser.

The upper ends of the feed-point bar and presser bar are pivoted by horizontal pins 165, 167 in forked opposite ends of the horizontal arm 169 of an inverted T-shaped plate, the upwardly projecting arm 171 of which is also forked to receive a block 173 fulcrumed in the fork on a pin 175 extending across the fork. The block is straddled by the slotted end of a bell-crank lever 177 pivoted on a horizontal stud 179 fixed in the head of the machine frame. The other arm of the bell-crank lever is forked to embrace a cam 181 on the forward end of the cam shaft of the machine. A stop shoulder 183, formed on a vertically adjustable block 184, on the front cap of the head of the machine frame, is arranged to engage a boss on the forked arm of the T-shaped plate to which is pivoted the upper end of the feed-point bar, to limit the downward movement of the feed-point. A second stop shoulder 185, formed on the block 184, is engaged by the opposite side of the boss to prevent upward movement of the feed-point and presser under the influence of the horn-raising spring when work is placed in the machine. When the bell-crank lever 177 is rocked on its pivot by the cam on the cam shaft, the T-shaped plate will also be rocked and will first lower either the feed point or presser, whichever is at the time raised, on to the work, and will then raise the other of the two members using its connection with the upper end of that member which it has just lowered as the fulcrum.

The cam shaft is extended through the cap aforementioned and on its end has a hand wheel 186 whereby the cam shaft may be readily turned by the operator standing conveniently in operating position.

On the cam shaft just behind the needle actuating crank is a bevel pinion 187 meshing with a second bevel pinion 188 on the upper end of a vertical shaft 189, there being interposed between the second pinion and the shaft a customary form of safety

device 191 such, for instance, as is disclosed in British Patent No. 13,579 of 1895, permitting interruption of the drive on excessive resistance to rotation of the shaft.

5 This vertical shaft is connected as usual by bevel pinions and a horizontal shaft to a bevel pinion 193 through which slides vertically the vertical whirl driving pinion shaft of the horn as the horn moves vertically, the latter shaft being appropriately keyed to the pinion through which it slides.

Just below a yoke in which the horn is free to rotate (and which carries horizontal pins, one of which is shown at 195, to which 15 links, of which one is shown at 197, connect a treadle 198 mounted on the base of the frame, by which the horn is raised and lowered) is a horizontal edge cam 199 fast to the horn the rotation of which cam in company with the horn moves a roll 201 on 20 one arm of a bell-crank of a driving mechanism control hereinafter detailed, the cam being wide enough to engage the roll in all vertical positions of the horn.

25 It will be understood that the treadle 198 aforementioned is employed when work is to be introduced into the machine to lower the horn from the position of rest in which it is held by a compression spring 203 acting 30 on the vertical rod 3 aforementioned to hold the mechanism in a normal position determined by a stop (not shown), the lower end of the rod 3 being pivotally connected with the rear end of the treadle 198.

35 At the rear of the machine head where the cam shaft projects therefrom the latter carries the driving and stopping mechanism. The cam shaft passes through and projects beyond a casing 205 fast to the rear of the 40 machine head and which encloses swash-plate clutch-cone-actuating mechanism as illustrated and described in said patent to Jerram 1,124,620 aforesaid, the rear face 207 of the casing acting as the brake face against 45 which the front face of the clutch cone 209 is braked. On the cam shaft where it projects from the casing is a sleeve 210 confined on which between collars at the ends of the sleeve are, as relatively rotatable members, (a) a coned member 211 to cooperate with the clutch cone, (b) a brake drum 213 and (c) a belt pulley 215. The collar the 50 more remote from the rear end of the shaft is urged to that end of the shaft by springs not shown which act to displace the collar and sleeve 210 rearwardly when a manually operable cam lever 217 on the end of the shaft (the cam of which engages the rearward end of the sleeve) is swung into the 55 position shown by dotted lines in Fig. 1, allowing such movement of the sleeve, the coned member 211 carried by the sleeve being thus moved out of range of the clutch cone 209 and it then being impossible to 60 start the machine by power, the arrange-

ment, however, permitting of the machine, on depression of the clutch treadle to separate the member 209 from the braking face, being turned by hand.

55 Mounted directly side by side on the sleeve 210 between the collars on the ends of the sleeve are two sleeves, fast to the forward one 219 of which is the coned member 211 and to the rearward one 221 of which the belt pulley is fast. At their adjacent edges the sleeves each have formed a pinion, the rearward one 223 being larger than the forward one 225, meshing with appropriate pinions of a set of pinion pairs 226 each set constituted by a pinion meshing with each of the pinions formed on the sleeves and both fast on one shaft 227 mounted in bearings in the brake drum 213. The brake drum is mounted on the sleeves 219 and 221. The meeting edges of the sleeves are overlapped 80 and house between them roller clutch members 229 which when the brake drum is free to rotate clutch together the sleeves 219, 221, when rotating at the same speed, it being understood that when the brake drum is 85 stationary, and through the agency of the pinion pairs the forward sleeve is driven faster, that sleeve will overrun the roller clutch members.

90 Pivoted on and so as to hang from a bracket on the casing 205 are two brake shoes 230 encircling the brake drum and having their lower ends connected by a toggle 231, the toggle joint of which is connected to one end of an arm 233 fast on a 95 horizontal rock shaft 235 parallel with the cam shaft in a bearing on the casing. This rock shaft has fast on it a second arm 237 connected to the upper end of a rod 239 formed of two parts connected by a turn 100 buckle 241 allowing of variation in the 105 length of the rod.

The contacting surfaces of the brake drum 213 and shoes 230 are beveled so that as the shoes grasp the drum they wedge it towards the rear end of the shaft and away from the end face of the coned member with which it has been held in driving contact by springs 243, during the joint movement of the drum and coned member.

110 The lower end of the rod 239 is pivoted to one arm of a bell crank lever 245 itself pivoted by a horizontal pivot 247 to one extremity of a horizontal lever 249 pivoted on the column to extend towards the rear of the machine. A tension spring 251 one end of which is anchored to the lever 249 and the other end to the lever 245 urges the latter relatively to the former in a direction to move a thrust rod 253 connecting the bell 115 cranks 245 and 202 forwardly of the machine to hold the cam roll 201 up to its cam 120 199.

125 A second spring 255 acts on the horizontal lever 249 to hold it against a stop 257 in 130

which position the lever acting through the lever 245 and rod 239 holds the toggle straightened and the brake drum 213 is free.

A clutch controlling rod 259 extends vertically upward from the rear end of a clutch treadle 261 and passes loosely through an opening in a lateral ear 263 on the horizontal lever 249, the rod having a little below the ear a shoulder 264 by which the controlling rod after it has risen sufficiently to throw in the clutch may be caused on further movement to raise the horizontal lever 249 and apply the brake to increase the speed of the machine, while nevertheless leaving the cam 199 free to reduce the speed owing to the yielding connection of the levers 245 and 249. At the upper end the controlling rod is pivoted to one arm of a bell crank lever 265 pivoted on the machine head and the other arm of which is pivoted to the link by which the clutch illustrated and described in the patent to Jerram No. 1,124,620 aforementioned is controlled. A spring 269 connected with the treadle 261 tends to lower the controlling rod to normal position. The downward movement of the rod is limited by a stop screw 267 adjustably threaded through a lug on the bell crank and arranged to engage a face on the machine.

As further indicating the nature of the machine detailed, it may be stated that certain of its parts are timed to move as follows:—

Considering the revolution of the cam shaft, which makes a complete revolution for each stitch cycle, and commencing with the shaft in its normal stopping position, the needle falls gradually during the first 150° of the revolution of the shaft remaining substantially stationary for some 20° to 30° to rise again gradually to reach its upper limit after some 310° of rotation of the shaft. The horn lock comes into operation after some 100° of rotation of the shaft to hold the horn from rising, the horn being released after the shaft has all but completed its revolution.

As the shaft commences its rotation, the feed point completes its rising movement, and its return movement away from the needle path, which commenced with the lift, is continued after the latter ceases until it itself terminates after some 50° rotation of the shaft. When the shaft has turned about 130° the point commences to fall and when it is down the presser foot (at about 170°) commences to lift completing its rise at about 210° when shortly thereafter (at about 230°) the lateral feed commences continuing to about 320° when the presser foot commences to fall once more completing its fall at about 350° just before the feed point commences to lift. The cast off commences to descend at about 50° completing its gradual descent at about 130° re-

maining in its position up to about 210° when it gradually rises to its raised position which it reaches at about 310°.

It is to be noted that in the construction shown the linkage used for connecting the needle actuating mechanism and the horn is such that as the needle descends into the work there is an increasing upthrust on the horn—a factor important in various ways in producing a good seam. The converse action, however, tends to cause a descent of the horn if the needle should meet undue resistance in the upward movement and although this tendency is opposed by the spring upholding the horn it may unexpectedly lower the horn a considerable amount. This lowering is no serious objection in itself but as the horn spring will cause the horn to spring upwards as soon as the resistance to needle movement is overcome the work may be suddenly squeezed at a time when this squeezing action will interfere with the feed and it is an important result of the horn locking mechanism provided in the construction described that if the horn should be so lowered it is prevented from rising until a definite time in the cycle when its sudden rise is immaterial.

While the features above described are well adapted for use in a shoe sole sewing machine, it is to be understood that, except as defined in the claims, certain features of the invention are not limited to use in a sewing machine. The means shown and described for varying the speed of operation as different parts of the shoe are being operated on forms the subject matter of a divisional application Serial No. 617,737, filed Feb. 8, 1923.

The nature and scope of the present invention having been indicated and a machine embodying the several features of the invention in their preferred form having been specifically described, what is claimed as new is:

1. A shoe sewing machine having, in combination, a needle, mechanism for actuating the needle comprising an oscillating lever, two links pivotally connected to turn about a common axis, a pivotal connection between one of said links and said oscillating lever, connections between the other link and the needle, a presser foot, a work support, and a connection acting upon a change in the relative position of the presser foot and work support to swing said pivotal connection of said links about the axis of said pivotal connection between one of the links and the oscillating lever to vary the needle stroke.

2. A shoe sewing machine having, in combination, a needle, mechanism for actuating the needle comprising an oscillating lever, a link, two links pivoted on the first mentioned link to turn about a common

axis, a pivotal connection between one of said two links and said oscillating lever, connections between the other of said two links and the needle, a presser foot, a work support, and a connection comprising the first mentioned link acting upon a change in the relative position of the presser foot and work support to swing the pivotal connection of said two links with the first mentioned link about the axis of said pivotal connection between one of the links and the oscillating lever to vary the needle stroke.

3. A shoe sewing machine having, in combination, a needle, mechanism for actuating the needle comprising an oscillating lever, two pivotally connected links, a pivotal connection between one of said links and said oscillating lever, connections between the other link and the needle, a presser foot, a work support, and a connection comprising a lever fulcrumed at its forward end on the frame of the machine and having its outer end pivotally connected with the work support, and a link having one end pivotally connected with said lever midway between its ends and having its other end pivotally connected with both of said two links acting upon a change in the relative position of the presser foot and work support to swing the pivotal connection of said two first mentioned links about said pivotal connection between one of the links and the oscillating lever to vary the needle stroke.

4. A shoe sewing machine having, in combination, a needle, mechanism for actuating the needle comprising a shaft provided with a crank, an oscillating lever fulcrumed on an axis transverse to the axis of said shaft, a connecting rod having universal joint connections at its ends with the crank and oscillating lever, two pivotally connected links, a pivotal connection between one of said two links and said oscillating lever, connections between the other link and the needle, a presser foot, a work support, and a connection acting upon a change in the relative position of the presser foot and work support to swing the pivotal connection of said links about the center of said pivotal connection between one of the links and the oscillating lever to vary the needle stroke.

5. A shoe sewing machine having, in combination, a needle, and mechanism for actuating the needle comprising a shaft provided with a crank, an oscillating lever fulcrumed on an axis transverse to the axis of said shaft, a connecting rod having universal joint connections at its ends with the crank and oscillating lever, and connections between the oscillating lever and the needle.

6. A sewing machine having, in combination, a needle, needle actuating mechanism, a presser foot, a work support movable toward and from the presser foot to caliper

the work, and a device acting to lock the work support from movement during a predetermined portion of a cycle of operations of the machine.

7. A shoe sewing machine having, in combination, a straight hook needle, needle actuating mechanism, a presser foot, a shoe supporting horn movable toward and from the presser foot to caliper the work, and a device acting to lock the horn from movement during the retracting stroke of the needle. 70

8. A shoe sewing machine having, in combination, a straight hook needle, needle actuating mechanism, a presser foot, a shoe supporting horn, means for yieldingly urging the horn toward the presser foot, and a device acting to lock the horn from movement during the retracting stroke of the needle. 80

9. A shoe sewing machine having, in combination, a needle, needle actuating mechanism, a presser foot, a work support movable toward and from the presser foot to caliper the work, connections between the work support and needle actuating mechanism to vary the limit of one of the strokes of the needle as variations occur in the thickness of the work, and a device acting to lock the work support from movement during the retracting stroke of the needle. 90

10. A shoe sewing machine having, in combination, a straight hook needle, needle actuating mechanism, a presser foot, a shoe supporting horn, means for yieldingly urging the shoe supporting horn toward the presser foot, connections between the work support and needle actuating mechanism to vary the work piercing stroke of the needle as variations occur in the thickness of the work, and a device acting to lock the shoe supporting horn from movement during the retracting stroke of the needle. 100

11. A shoe sewing machine having, in combination, a needle, needle actuating mechanism, a presser foot, a work support movable toward and from the presser foot to caliper the work, connections between the work support and needle actuating mechanism to vary the limit of one of the strokes of the needle as variations occur in the thickness of the work, a longitudinally movable rod associated with said connections between the work support and needle actuating mechanism, and cam controlled means 110 acting on the rod for locking the work support from movement during the retracting stroke of the needle.

12. A sewing machine having, in combination, a needle, needle actuating mechanism, a presser foot, a work support movable toward and from the presser foot to caliper the work, and a device acting to lock the work support from movement during a predetermined portion of a cycle of operations 115

- of the machine comprising a longitudinally movable rod, a shaft, a friction shoe mounted on the shaft to engage the rod, a yielding connection between the shaft and friction shoe, and cam controlled means for actuating the shaft to yieldingly urge the friction shoe against the rod.
13. A shoe sole sewing machine having, in combination, a straight barbed needle, a shoe supporting horn, a presser foot, a feed member, and means for actuating the presser foot and feed member rendered operative to withdraw one of these parts from the work by the engagement of the other part with the work comprising an oscillating lever, a member having a horizontal portion pivotally connected at its ends with the presser foot and feed member respectively, and having a substantially vertical portion, and a pivotal connection between the vertical portion of said member and the oscillating lever constructed to permit relative vertical movement of said member and said lever.
14. A shoe sole sewing machine having, in combination, a straight barbed needle, a shoe supporting horn, a presser foot, a feed member, means for actuating the presser foot and feed member rendered operative to withdraw one of these parts from the work by the engagement of the other part with the work, a stop for limiting the downward movement of the presser foot, and a spring having one end engaging the presser foot for urging the presser foot toward the work.
15. A shoe sole sewing machine having, in combination, a straight barbed needle, a shoe supporting horn, a presser foot, a feed member, an oscillating member connecting the presser foot and feed member for withdrawing one of these parts from the work by the engagement of the other part with the work, and a spring for urging one only of these parts toward the work at all times.
16. A shoe sole sewing machine having, in combination, a straight barbed needle, a shoe supporting horn, a presser foot, a feed point, and means for actuating the presser foot and feed point rendered operative to withdraw one of these parts from the work by the engagement of the other part with the work comprising a member connecting the presser foot and feed point, an actuating member, a pivotal connection between the actuating member and said member connecting the presser foot and feed point constructed to permit relative vertical movement of said members, and means for limiting the extent of the vertical movements of said presser foot and feed point.
17. A shoe sole sewing machine having, in combination, a shoe supporting horn, a straight hook needle, a shaft extending from front to rear of the machine and provided with a crank, and a lever and link connection between the needle and crank for actuating the needle having the levers and links arranged with their axes transverse to the axis of the shaft.
18. A shoe sole sewing machine having, in combination, a straight hook needle, a rotary shoe supporting horn, a shaft extending from front to rear of the machine, a lever and link connection between the needle and the shaft having the levers and links arranged with their axes transverse to the axis of the shaft, a variable speed driving mechanism mounted on the rear end of the shaft, and connections between the variable speed driving mechanism and the horn for varying the speed of the machine as different portions of the shoe are operated upon.
19. A shoe sole sewing machine having, in combination, a straight hook needle, a presser foot, a shoe supporting horn movable toward and from the presser foot to caliper the work, a shaft extending from front to rear of the machine, a lever and link connection between the needle and the shaft having the levers and links arranged with their axes transverse to the axis of the shaft, and connections between the shoe supporting horn and the connections between the needle and shaft for varying the strokes of the needle in accordance with variations occurring in the thickness of the work.
20. A sewing machine having, in combination, a needle, needle actuating mechanism, a presser foot, a work support movable toward and from the presser foot to caliper the work, and means for locking the work support and for raising the presser foot during the feed.
21. A sewing machine having, in combination, a needle, needle actuating mechanism, a presser foot, a work support movable toward and from the presser foot to caliper the work, means for raising and lowering the presser foot, and means acting to lock the work support before the foot is raised and to release it after the foot is lowered.
22. A sewing machine having, in combination, a needle, needle actuating mechanism, a presser foot, a work support, means for yieldingly urging the work support toward the presser foot, means for raising and lowering the presser foot, and means acting to lock the work support before the foot is raised and to release it after the foot is lowered.
23. A sewing machine having, in combination, a needle, needle actuating mechanism, a presser foot, a shoe supporting horn, means for yieldingly urging the shoe supporting horn toward the presser foot, connections between the horn and needle actuating mechanism to vary the stroke of the needle as variations occur in the thickness of the work, means for raising and lowering the presser foot, and means acting to lock the

work support before the foot is raised and to release it after the foot is lowered.

24. A sewing machine having, in combination, a needle, a presser foot, a feed member, means for actuating the presser foot and feed member rendered operative to withdraw one of these parts from the work by the engagement of the other with the work, a work support, means for yieldingly urging the work support toward the presser foot, and a stop for limiting the upward movement of the feed member and presser foot.

25. A sewing machine having, in com-

bination, a needle, a presser foot, a feed member, means for actuating the presser foot and feed member rendered operative to withdraw one of these parts from the work by the engagement of the other with the work, a work support, means for yieldingly urging the work support toward the presser foot, a stop for limiting the upward movement of the feed member and presser foot, and means acting to lock the work support while the feed member is in engagement with the work.
